(57) **CLAIM**

The ornamental design for a vacuum de-aeration pump, as shown and described.

DESCRIPTION

FIG. 1 is a perspective top view of the vacuum de-aeration pump.

FIG. 2 is a perspective bottom view of the vacuum de-aeration pump.

FIG. 3 is a side elevation of the vacuum de-aeration pump.

FIG. 4 is a side elevation of the vacuum de-aeration pump.

FIG. 5 is a front elevation of the vacuum de-aeration pump.

FIG. 6 is rear elevation of the vacuum de-aeration pump.

FIG. 7 is top view of the vacuum de-aeration pump; and,

FIG. 8 is a bottom view of the vacuum de-aeration pump.
